UNITED STATES PATENT OFFICE.

CHARLES KASTENBEIN, OF CLAPHAM ROAD, ENGLAND, ASSIGNOR TO
EDWARD L. FORD, OF BROOKLYN, NEW YORK.

IMPROVEMENT IN TYPE-COMPOSING MACHINES.

Specification forming part of Letters Patent No. 140,279, dated June 24, 1873; application filed
January 8, 1873.

To all whom it may concern:

Be it known that I, CHARLES KASTENBEIN, of Clapham Road, in the county of Surrey, England, have invented an Improved Type-Composing Machine, of which the following is a specification:

Figure 1 is a perspective view, showing the front and one side of the composing-machine and the back of the justification-desk. Fig. 2 is a front view of the justification-desk with its justifying-frame. Fig. 3 shows the perpendicular shield of the composing-machine, with conduit, pusher, and cam-wheel. Fig. 4 is a vertical sectional view through the type-reservoirs, conduit, and finger-keys.

The types are supported one upon the other in vertical compartments A B, the compartment A containing roman type, and the compartment B containing italics and small capitals. These compartments are formed by metallic plates *a* facing each other, and having grooves cut in their inner surfaces, in which are inserted partitions *b* *c*, Fig. 4, the partitions in the compartment A being in the form shown at *b*, and those in the compartment B in the form shown at *c*. These partitions are placed at such distances apart as to correspond with the thickness of the tubes which contain the types. These tubes *P* (see Figs. 1 and 4) are made of thin sheet metal, the width of each tube corresponding with the thickness of the type which it contains. The types are placed in the tubes, one upon another, the roman type with the nicks downward and the italics and small capitals with the nicks upward, and the tubes are placed in the compartments so that the faces of the types in the two compartments are toward each other. This disposition is made so that the two kinds, being thrust forward from opposite directions, they may be faced in the same direction when turned to descend to the setting-point. When a tube is exhausted of its supply of type it is replaced by a full one. When in place in the compartments the lower ends of the tubes rest upon reglets *d*, immediately under which are the pushers *C* and *D*, the points *e* of which are of the same thickness as that of the types which they respectively operate upon. The pushers *C* for the roman types are connected by bell-cranks *m* and rods

l with the keys *L*, which are arranged in four banks, of twenty-four keys each, near the lower part of the machine. The pushers *D*, for the italics and small capitals, have the keys *R* on their outer ends, and are arranged near the bottom of the compartment *B*, and are attached to, and work in, the frame-work which supports said compartment *B*, said frame-work being hinged to the upper portion of the machine, as shown at *Q*, so that it may be opened when necessary. *L¹* *L²* *L³* *L⁴* represent the levers, to which the keys *L* are attached, showing the different shapes in which they are necessarily made in order to facilitate their arrangement in the different banks. The pushers *C* are provided with springs *o*, and the pushers *D* are provided with springs *t*, which springs tend to hold the pushers in the positions shown in Fig. 4, when not in operation. The metallic plates *a*, which form the outer sides of the compartments *A* and *B*, have their lower edges inclined downward and inward toward each other, as shown in Fig. 4, so as to form a hopper or trough, open at the bottom, and communicating with the upper end of the shield *E*, which is located immediately under it. The shield *E*, (see Fig. 3,) consists of a metallic plate, having ninety-six grooves formed in its face, corresponding in number and dimensions with the compartments in the cases *A* and *B*. The upper ends of the grooves communicate with the compartments containing the types, and their lower ends terminate in a spout, *F*, in which are two balances, *f* and *g*, the balance *g* to prevent the type from turning, and the balance *f* to convey the type into the conduit *G*, into which the spout empties. The conduit *G* is a long, twisted horizontal passage, wherein the type at first stands upright, and is gradually pushed along in an inclined position to the justification-desk *M*. On the conduit *G*, beneath spout *F*, is a spring, *h*, which holds the last-conveyed type, and on the left of the conduit is the pusher *H*, which pushes the type along. This pusher is advanced by a cam-wheel, *I*, which receives its motion from the pedal *K*.

The justification-desk *M* (see Fig. 2) contains a galley, *N*, provided with an adjustable side-stick, *N'*, and similar in its purpose to an or-

inary composing stick, but much longer. The lines are justified in this galley, and the justified matter is pressed down by the slide-bar T, operated by the pedal O, through the medium of rod S and lever s. (See Figs. 1 and 2.) The galley is taken out when full and replaced by an empty one.

Two operators are required for the successful operation of this machine—one to compose and the other to justify the matter. As the compositor presses one of the keys L the rod land bell-crank m are drawn down, moving forward the pusher C, the point e of which pushes out the lowermost type in the compartment A, and causes it to fall with its face on the ledge n. When the key is released the spring o draws the pusher C, lever m, rod l, and key L back to their original positions, leaving the type free to fall into its corresponding partition p in the shield E, and through spout F into conduit G, where the words are formed and pushed along by pusher H.

When italics or small capitals are wanted the compositor presses the keys R attached to the outer ends of the pushers D, which operate on the types in the compartment B in the same manner as the pushers C operate on those in the compartment A. When pressure is withdrawn from the keys R they are drawn back to their former positions by the springs t. The conduit is provided with a spring to prevent the first type from falling. When the types in the conduit reach the justification-desk M, the operator in front of the same cuts a line to its required length and pushes it into the galley N on the spring-slide q; he then moves the pedal O with his foot, pushing the slide-bar T above the line down into the galley, where it is justified. The operation is repeated until the galley is full, when it is replaced by an empty one. At the end of the conduit a plate, r, is placed against the type to prevent it from falling.

Before being introduced into the tubes P the types are assorted by a distributing-machine, which works in connection with the composing-machine, and the construction and operation of which are somewhat the reverse of what has just been described in respect to the composing-machine.

The essential and peculiar features of the distributing-machine I have described and

claimed in a separate application for Letters Patent.

Having thus described my improved apparatus for composing type, what I claim as new therein, and desire to secure by Letters Patent, is—

1. In a type-composing machine, two parallel ranges of close boxes A and B for containing the type, said boxes being formed of the plates a a and partitions b c, substantially as hereinbefore described.

2. The relative arrangement of the vertically-moving keys L, and horizontally-moving keys R, operating in combination with the pushers C and D, respectively, substantially as and for the purposes set forth.

3. The reglets d and ledges n, when arranged as herein described, below the vertical parts of boxes A B, of the construction specified, and above the inclined or converging bottoms of said boxes, by which the different types are conducted to a common plane for delivery into the shield.

4. The pusher C or D, constructed with a bifurcated end with the lower portion prolonged, as shown in Fig. 4, to adapt it to catch the heel of the type as it is discharged from the reglet d, and operating in combination with the ledges n to drop the said type in proper position as the pusher recedes.

5. The pivoted guides f and g, placed in the throat F, and adapted to operate substantially as herein described, for the purposes set forth.

6. The twisted conductor G, extending laterally from the throat F of the vertical shield E, and arranged as described, to take the type in vertical position from the said shield and deliver it in inclined position face forward to the justification-desk.

7. The combination of two ranges of boxes A and B, connected by a hinge, Q, to admit of their ready separation, as explained, when required.

8. The justification-desk provided with a removable galley, N, and a slide-bar, T, the latter operated by pedal O, through the medium of rod S and lever s, substantially as described.
